UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET HANDLE.

43,264.

Specification for Design.

Patented Nov. 26, 1912.

Application filed October 7, 1911. Serial No. 653,416. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawing, forming a part thereof.

The figure presented is a front elevation of a burial-casket handle, showing my new and particular design herein emblazoned or

displayed on its several constituent or component parts that include thereunder the attaching-plate, the pivotal pendent hanger lugs or arms and the tipped end of the horizontal handle-bar, such handle-bar itself being shown broken off.

I claim:—

The ornamental design for a burial-casket handle as shown and described.

CHARLES BLESCH.
